Term of patent 14 years

(Cl. D36—2)

T1 Q.1.

FIG. 1 is an elevational view of a footed bowl or similar article showing my design;

FIG. 2 is a bottom view thereof;

FIG. 3 is a sectional view taken along line 3-3 of FIG. 1;

FIG. 4 is an elevational view of a sector of the design appearing on the side of the footed bowl shown in FIG. 1;

FIG. 5 is a sectional view taken along line 5-5 of FIG. 1; and

FIG. 6 is a sectional view taken along line 6-6 of FIG. 3.

It is understood that the patterns shown fragmentarily in full lines are continued about the entire article in the paths indicated by the broken lines.

The present application is a division of co-pending United States design patent application Ser. No. 7,309, filed May 31, 1967.

I claim:

The ornamental design for a footed bowl or similar article, substantially as shown and described.
